PATTERN WHEEL CONTROL SYSTEM

William L. Carroll, 328 N. Newlin, Whittier, Calif.
Filed Mar. 30, 1962, Ser. No. 183,836

9 Claims. (Cl. 66—50)

This invention relates to a pattern control system for circular knitting machines and, more particularly, to a pattern wheel adapted to be utilized in conjunction with a plurality of similar wheels to control the pattern which is being knitted into the fabric of a conventional rotary knitting machine.

Rotary knitting machines, as is well known to those skilled in the art, customarily include a fixed bed and a rotatable bank of needles to which the yarn is fed from appropriate bobbins or spindles.

They also include, alternatively, a rotatable bed and a fixed bank of needles. The present invention is applicable to either arrangement, but will be described hereinbelow as applied to a fixed bed type of machine. The yarns are of different colors and are adapted, upon proper actuation of the needles, to create a chosen pattern in the fabric being knitted. In conventional knitting machines of the character under discussion, the pattern of the fabric being knitted is established by a plurality of rotatable pattern wheels which are mounted upon the fixed bed of the machine in proximity to the rotating bank of needles and which are adapted to be rotated synchronously with said bank of needles by engagement with adjacent butt portions of seed needles.

Conventional rotatable pattern wheels include a plurality of needle-actuating jacks which must be painstakingly set manually in either extended or retracted positions by a skilled mechanic in order to establish the needle actuating pattern of said jacks. Therefore, each time a pattern is changed it is necessary to alter the position of the jacks in a plurality of pattern wheels mounted in association with the knitting machine.

It is therefore, an object of my invention to provide a pattern control system for a circular knitting machine of conventional character which includes a plurality of pattern wheels, each of which has an individual pattern associated therewith and adapted to dispose the jacks incorporated therein in predetermined pattern creating positions without the necessity for the manually adjustment of said jacks prior to the operation of the knitting machine. Therefore, the time consuming pattern wheel setting characteristic of conventional wheels is eliminated and a pattern on a particular knitting machine incorporating pattern wheels of the invention may be changed by the mere expedient of changing the patterns associated with the pattern wheels of the invention.

Another object of my invention is the provision of a pattern wheel of the aforementioned character wherein the pattern wheel includes a rotatable housing and incorporates a plurality of jacks having portions protruding through openings in the wall of said housing and adapted to be selectively received in corresponding openings in said pattern or rejected by blank areas of said pattern and whereby said jacks may be, respectively, extended from or retracted into said housing.

An additional object of my invention is the provision of an individual pattern for the aforementioned pattern wheel which is constituted by an endless loop of perforated tape formed from relatively strong material, such as the synthetic plastic Mylar and polyethylene, the apertures in said tape being adapted to receive the protruding portions of the aforementioned jack, to permit said jacks to remain in extended positions with respect to the associated housing and the non-apertured portions of said tapes being adapted to reject said protruding por-

2

tions of said jacks to urge said jacks into retracted positions with respect to said housing.

An additional object of my invention is the provision of a pattern wheel of the aforementioned character in which the aforesaid pattern issues from a magazine which is operatively connected to the pattern wheel and whereby the pattern can be continuously issued from said magazine to control the location of the jacks of said pattern wheel.

Another object of my invention is the provision, in a pattern wheel of the aforementioned character, of a magazine adapted to receive an endless loop of pattern tape which continually issues from and is returned to said magazine, respectively, prior to and subsequent to its pattern forming function.

The implications of the teachings of the invention will be readily apparent to those skilled in the art. In the first place, the provision of pattern wheels constructed in accordance with the teachings of the invention and actuated by a tape-type pattern eliminates the painstaking and tedious labor involved in the manual setting of the jacks on conventional pattern wheels.

Moreover, with conventional pattern wheel constructions it is necessary that the rotation of the pattern wheels be exactly synchronized with the rotation of the needle bank because of the fact that the pattern is rigidly established by the pattern wheels and any lack of synchronization would destroy the pattern effect. By utilizing the pattern wheels of the present invention, complete flexibility of the pattern wheels with respect to the needle bank is achieved because of the fact that the tape-type pattern eliminates the necessity for the synchronization of the pattern wheels with the rotating needle bank.

Of course, with conventional pattern wheels the pattern field is limited to a series of repetitive effects since each rotation of each pattern wheel can contribute only to the predetermined number of pattern forming impulses to the needles of the needle bank of the knitting machine. However, by the utilization of a plurality of pattern wheels constructed in accordance with the teachings of the invention, it is possible to achieve an endless variety of pattern effects due to the fact that the pattern may be continuously altered as the pattern tape is rotated past the protruding portions of the jacks to energize the same.

The consequences of such flexibility of action are obvious since the tapes constituting the pattern tapes are formed from relatively thin material and an exceedingly large number of pattern creating apertures can be formed therein. Moreover, the pattern magazines can be readily removable from operative relationship with the associated pattern wheel housings so that the patterns may be readily changed in order that short runs of fabric may be achieved with a minimum expenditure of time and effort.

Consequently, Jacquard effects can be achieved by the use of the pattern wheel control system of the invention without the necessity for extensive modification of the conventional machines to which it is applied. Thus, pattern effects of practically infinite variety can be achieved.

Other objects and advantages will be apparent from the following specification and the accompanying drawings which are for the purpose of illustration only and in which:

FIG. 1 is a side elevational view of a rotary knitting machine having the pattern control system of the invention installed thereupon;

FIG. 2 is an enlarged, fragmentary plan view showing the installation of pattern wheels of the invention in operative relationship with the perimeter of said knitting machine;

FIG. 3 is an enlarged, fragmentary sectional view show-

ing the installation of one of the pattern wheels of the invention in operative relationship with the needle bank of a typical knitting machine;

FIG. 4 is a side elevational view of a pattern wheel constructed in accordance with the teachings of my invention;

FIG. 5 is a top plan view of the pattern wheel;

FIG. 6 is a vertical sectional view taken on the broken line 6—6 of FIG. 4;

FIG. 7 is an enlarged, fragmentary sectional view showing the manner in which the needle actuating jacks of the pattern wheel are controlled by the associated control pattern;

FIG. 8 is a view similar to FIG. 7 showing the retraction of a needle actuating jack of a pattern wheel to permit a needle to remain inoperative; and

FIG. 9 is an exploded view showing the various components of the pattern wheel of the invention.

Referring to the drawings, and particularly to FIGS. 1-3 thereof, I show a circular or rotary knitting machine 10 which includes a base 12 supporting a bed 14, said bed having a rotatable bank 16 of needles 18 associated therewith. The rotatable bank 16 of needles 18 is supplied with yarn 20 from appropriate sources, not shown, so that the needles may knit a length of fabric 22.

Operatively associated with the bank 16 of needles 18 is the pattern control system 30 of the invention, said pattern control system being constituted by a plurality of pattern wheels 32 mounted on the bed 14 in immediate proximity to the rotatable bank 16 of needles 18. For purposes of clarity in illustration, only relatively few pattern wheels 32 have been shown in FIG. 1 of the drawings. However, it is intended that thirty pattern wheels 32 be mounted on the bed 14 of the circular knitting machine 10 in order that the pattern control system 30 of the invention may function as effectively as possible, as best shown in FIG. 2 of the drawings.

Each of the pattern wheels 32 includes a substantially circular housing 34 which is angularly mounted on a bracket arm 36 by means of a bolt 38 whose lower extremity is engaged by a nut 42, as best shown in FIGS. 3 and 6 of the drawings. It will be noted that each pattern wheel 32 is angularly oriented with respect to the bank 16 of needles 18 in order that, in a manner to be described in greater detail below, the needles 18 may be actuated to engage a length of yarn 20.

Each pattern wheel 32, as best shown in FIGS. 4-9 of the drawings includes a base 44 having a plurality of perimetrical slots 46 formed therein. The base 44 is provided with steps 48 and 52 as its perimeter in the region of 50

55

Mounted upon the base 44 is a cylindrical wall 54 which incorporates a plurality of guide pins 56, for a purpose which will be referred to in greater detail hereinbelow. The cylindrical wall 54 is shown in FIGS. 7 and 8 of the drawings, as curved in vertical cross section and includes banks 58 and 62 of openings 64 and 66, respectively. The apparent curvature of the wall 54 is due to the fact that the sections of FIGS. 7 and 8 are taken at a 30° angle to the vertical axis of the wheel 32. The openings 64 of the upper bank 58 are staggered with respect to the openings 66 of the lower bank 62 to permit sufficient edge distance between said openings. The upper edge of the cylindrical wall 54 incorporates a continuous, annular concavity 72 whose inner wall is provided with a plurality of guide slots 74, as best shown in FIG. 9 of the drawings.

Disposed within the cylindrical wall 54 and in spaced relationship therewith is a ring 76 incorporating a plurality of angularly oriented slots 78 in its perimeter. The ring 76 is disposed in encompassing relationship with an upwardly directed boss 82 formed integrally with the base 44, as best shown in FIG. 9 of the drawings. It will be noted that the peripheral wall of the ring 76 is shown as curved in the plane of the slots 78 for the reasons explained above.

5

Mounted in overlying relationship with the wall 54 and ring 76 is a top plate 84 which, as best shown in FIGS. 7-9 of the drawings, incorporates in its underside adjacent the periphery thereof an annular concavity or groove 86 corresponding to the annular concavity 72 in the cylindrical wall 54 and mating therewith to define a retention chamber 88, as best shown in FIGS. 7-8 of the drawings. The top plate 84 incorporates a depending skirt 92 which, as best shown in FIG. 9 of the drawings, incorporates a plurality of threaded bores 94 adapted to receive bolts 96 or similar fasteners extending upwardly through corresponding openings 98 in the base 44. Also incorporated in the top plate 84 are openings 102 which correspond to threaded bores 104 in the ring 76 and which are adapted to receive fasteners 108 to maintain the ring 76 against displacement with respect to the top plate 84.

Therefore, when the base 44, cylindrical wall 54, ring 76, and top plate 84 are disposed in assembled relationship the lower edge of the cylindrical wall 54 is juxtaposed to the step 52, the ring 76 is disposed within the cylindrical wall 54, the peripheral edge of the top plate 84 engages the corresponding upper edge of the cylindrical wall 54 and the depending skirt 92 of the top plate 84 fits within the ring 76 and encompasses the upwardly directed boss 82 of the base 44 to maintain the various components of the pattern wheel 32 in concentric and operative relationship with one another. When so assembled, the bolts 96 extend upwardly through the corresponding opening 98 in the base plate 44 and engage the corresponding threaded bores 94 in the top plate 84, to maintain the top plate 84 in operative relationship with the base 44. Furthermore, the bolts 108 extend through the corresponding openings 102 in the top plate 84 to engage the threaded bores 104 in the ring 76.

25

30

35

40

45

A bushing 112 is, as best shown in FIG. 6 of the drawings, located within the upwardly directed boss 82 of the base 44 and encompasses the shank of the bolt 38 to permit relative rotation between the bolt 38 and the housing 34 of the pattern wheel 32. Moreover, there is defined between the cylindrical wall 54 and the perimeter of the ring 76 a jack chamber 116 which, as best shown in FIGS. 7-8 receives a plurality of jacks 120. In the present embodiment of the invention it is contemplated that one hundred and sixty (160) jacks be incorporated in the pattern wheel 32.

Each jack 120 includes a circular lobe 122 at its upper extremity which is received in the retention chamber 88 defined by the corresponding annular recesses 72 and 86 in the cylindrical wall 54 and top plate 84, respectively. Therefore, each jack 120 is adapted to pivot within the jack chamber 116.

50

55

60

65

70

75

Formed in each jack 120 intermediate its extremities is a slot 124 which is adapted, as best shown in FIGS. 7-9 of the drawings to receive the substantially right-angularly bent upper extremity 126 of a jack actuating spring 128 whose lower extremity 130 is received in the corresponding slot 78 of the ring 76. Therefore, the spring 128 associated with each jack 120 tends to bias the associated jack 120 outwardly toward the circular or cylindrical wall 54.

Each jack 120 has a substantially flat front edge 132 and there is formed thereupon a control protrusion or portion 134 of arcuate configuration which is adapted to be received in a corresponding opening 64 or 66 of the upper and lower banks 58 and 62, respectively of openings. Of course, as best shown in FIG. 7 of the drawings, the arcuate protrusions 134 which are received within the openings 66 of the lower bank 62 of openings are located upon the respective jacks 120 below the protrusions 134 of those jacks 120 which are received within the openings 64 of the upper bank 58 of the openings. Therefore, the jack actuating springs 128 normally tend to bias the protrusions 134 thereupon outwardly through the associated openings 64 and 66 beyond the perimeter of the external surface of the cylindrical wall 54.

Formed integrally with the lower extremity of each jack 120 is a guide portion 138 and a needle butt engaging and actuating portion 140. The guide portion 138 is adapted to move in the portion of the associated slot 46 formed in the upper step 52 of the base 44 while the needle butt engaging portion 140 is adapted to move in that portion of the associated slot 46 located in the lower step 48, as best shown in FIGS. 7-9 of the drawings. The associated spring 128 normally biases the jack 120 into an operative position in which the protrusion 134 thereupon projects through the associated opening 64, as best shown in FIG. 7 of the drawings. Therefore, the needle butt engaging and actuating portion 140 of the jack 120 is disposed in a position in which it may engage the butt 142 of an associated needle 18 to cause said needle to be lifted, as best shown in FIG. 3 of the drawings, into a position in which it will engage a length of yarn 20 and cause said length of yarn to be knitted into an appropriate pattern, as will be more clearly described hereinbelow.

The pattern wheels 32 are rotated by the bank 16 of needles 18 by engagement of the outer extremities of the slots 46 upon the needle shanks adjacent the butts 142 thereof and, therefore, a predetermined jack 120 will always register with a predetermined needle 18 in order that a predetermined pattern may be established in the fabric being knitted.

The bolt 38 has an enlarged cylindrical head 148 which, as best shown in FIG. 6 of the drawings, is located within the depending skirt 92 of the top plate 84 and encompassed by a bushing 152 which serves as a bearing between the head 148 and said skirt to permit relative rotation between the bolt 38 and the housing 34 of the pattern wheel 32. The cylindrical head 148 of the bolt 38 has a radially extending flange 154 upon the upper extremity thereof adapted to restrain the bushing 152 against displacement from its location between said head and the depending skirt 92 of the top plate 84.

Mounted upon the cylindrical head 148 of the bolt 38 by means of a bracket 162 and bolts 164 is a magazine 166 incorporated in a housing 168 formed integrally with the bracket 162. The magazine 166 is adapted to receive a continuous pattern 170 which is constituted by a continuous loop 172 of tape, said tape being formed from a suitable plastic such as vinyl, polyethylene, or the like.

The magazine 166 is of the type which feeds the return run 174 to the perimeter of the magazine and feeds the outgoing run 176 from the center of the magazine, as best shown in FIGS. 4 and 5 of the drawings. The pattern tape 172 is provided with guide openings 182 adjacent its opposite edges which, as best shown in FIGS. 7-8 of the drawings, are adapted to be engaged by the corresponding guide pins 56 mounted in the cylindrical wall 54. Engagement of the guide pins 56 in the guide openings 182 of the pattern tape 172 causes the pattern tape 172 to be drawn positively into encompassing relationship with the cylindrical wall 54 of the housing 34 of the pattern wheel 32 and to fit in snug engagement with the perimeter of said cylindrical wall.

Incorporated in the pattern tape 172, as best shown in FIG. 7 of the drawings, are pattern apertures or openings 178 which are adapted to permit the protrusions 134 on the jacks 120 to project through the pattern tape 172 to permit the butt engaging portions 140 of the jacks 120 to engage the corresponding butts 142 of the needles 18. However, where no openings are provided in the pattern tape 172, the jacks 120 are urged inwardly against the bias of the actuating springs 128 into the inoperative position shown in FIG. 8 of the drawings.

When the jacks 120 are located in the inoperative positions of FIG. 8 of the drawings, the butt actuating portions 140 are withdrawn into positions in which they cannot possibly engage the butts 142 of the needles 18 thus permitting the needles 18 to remain inoperative and thus

determining the pattern which is formed in the fabric being knitted.

When the rotary or circular knitting machine 10 is in operation, the pattern wheels 32 constituting the pattern control system 30 of the invention are continuously rotated with respect to the bed 14 upon which they are mounted. Such rotation occurs concomitantly with rotation of the needle bank 16 so that predetermined jacks 120 are rotated into proximity to selected needles 18 to either actuate said needles 18 or permit them to remain inoperative. The rotation of the individual pattern wheels 32 is accomplished by engagement of the extremities of the slots 46 in the base plate 44 with corresponding needles 18.

As previously indicated, the magazine 166 associated with each pattern wheel 32 is mounted fixedly upon the head 148 of the associated bolt 38 and, thus, the pattern wheels 32 rotate with respect to the associated magazines 166. Relative rotation of the pattern wheels 32 with respect to the fixedly mounted magazines 166 causes the continuous pattern 170 constituted by the continuous loop 172 of plastic tape to be drawn into operative relationship with the cylindrical wall 54 of the housing 34 of the associated pattern wheel 32.

Prior to installation in the magazine 166, the endless loop 172 of tape has been perforated to provide the pattern determining openings or apertures 178 therein and to establish a pattern which will be communicated to the fabric through the actuation or inactivation of the needles 18.

Therefore, when openings or apertures 178 are formed in the tape the protrusions 134 on the jacks 120 are permitted to pass through the tape. This permits the jacks 120 to move into positions in which the needle actuating portions 140 thereof engage the corresponding butts 142 of the needles 18 to permit said needles to pick up the yarn 20 and establish a pattern.

Obviously, an extremely long length of pattern tape 172 can be provided in the magazine 166, thus achieving a variety of patterns which is characteristic of that normally obtainable only by the utilization of relatively complex and expensive Jacquard knitting machines.

As can be readily visualized, the necessity for synchronizing the rotation of the pattern wheels 32 with the rotation of the needle bank 16 so that the jack always engages a predetermined needle is eliminated. This is attributable to the fact that the endless loop 172 of tape permits extreme flexibility of actuation of the jacks 120 and thus eliminates the necessity for absolute synchronization between the pattern wheel 32 and the associated bank 16 of needles 18.

Moreover, the endless pattern 170 can be readily changed to substitute alternative patterns therefor. This eliminates the considerable down time characteristic of prior art machines wherein the jacks of the pattern wheels had to be adjusted manually. Obviously, the extreme flexibility of the provision of individual endless patterns 170 for each pattern wheel 32 provides for a practically infinite pattern field since each pattern wheel is able to contribute to the ultimate pattern a far greater pattern expanse than was, of course, achievable by the utilization of prior art pattern wheels wherein the pattern was fixed by the mechanical positioning of one hundred and sixty jacks.

In other words, the provision of the endless loop 172 of pattern tape permits the individual jacks 120 to impart to the associated needles 18 of the bank 16 of needles a very large number of individual pattern forming impulses, thus greatly multiplying the effect of each pattern wheel 32 in its contribution to the pattern filed. The implications of this particular advance are obvious.

There is no necessity for extensive modification of the conventional circular knitting machine, and the relatively simple mounting of the pattern wheels 32 of the invention permits a conventional circular knitting ma-

chine to achieve results attainable previously only on Jacquard machines. Obviously, the saving in mechanics' time customarily expended in setting conventional pattern wheels is a significant economic factor. Furthermore, the long inoperative period resulting from the setting of the pattern wheels in conventional circular knitting machines is also eliminated.

I claim:

1. In a pattern wheel control system adapted to be utilized in conjunction with a circular knitting machine having a fixed bed and a rotating bank of needles on said bed, the combination of: a plurality of pattern wheels mounted on said bed adjacent said bank of needles, each of said pattern wheels having a plurality of slots engageable with said needles to drive said pattern wheel and an individual, continuous pattern associated therewith; a plurality of pivotal jacks in each of said pattern wheel retractable by the associated pattern to prevent said jacks from energizing an associated needle in said bank; and a magazine for said pattern fixedly mounted upon each of said pattern wheels.

2. In a pattern wheel construction adapted to be utilized in conjunction with a rotary knitting machine having a fixed bed and a rotating bank of needles mounted upon said bed, the combination of: a plurality of pattern wheels incorporating needle actuating jacks mounted on said bed in proximity to said bank of needles; a pattern magazine superimposed above each of said pattern wheels, said pattern magazine having its outlet and inlet immediately above said pattern wheel; and a jack actuating pattern in each of said magazines having a loop engageable with an associated wheel and the jacks therein.

3. In a pattern wheel construction adapted to be utilized in conjunction with a rotary knitting machine having a fixed bed and a rotating bank of needles mounted upon said bed, the combination of: a plurality of pattern wheels incorporating needle actuating jacks mounted on said bed in proximity to said bank of needles, each of said jacks being pivotally mounted in said pattern wheel and having an intermediate jack locating protrusion thereupon, each of said pattern wheels having a plurality of openings in its perimeter adapted to receive the protrusion of an associated jack; a spring engageable with each of said jacks for urging said protrusions through said openings; a pattern magazine fixedly mounted immediately above each of said pattern wheels and having its inlet and outlet in immediate proximity to said pattern wheel; and a jack actuating pattern in each of said magazines, each of said patterns being constituted by an endless tape which is continually fed to the perimeter of said pattern wheel to permit the extension of or cause the retraction of said jacks, said pattern having a plurality of protrusion receiving openings therein registerable with corresponding openings in an associated pattern wheel to permit movement of the protrusions of said jacks through said protrusion receiving openings of said pattern and to cause the extension of said jacks.

4. In a pattern controlling system adapted to be utilized in conjunction with a rotary knitting machine having a fixed bed and a plurality of knitting needles mounted for rotation in a bank on said bed, the combination of: a plurality of rotatable pattern wheels mounted on said bed of said knitting machine adjacent said bank of needles, each of said wheels having a perimetrical wall incorporating a plurality of jack openings intermediate its opposite edges and a plurality of pattern guides mounted in said wall adjacent said openings; a plurality of jacks movably mounted in each of said pattern wheels in juxtaposition to said wall, each of said jacks having a jack-actuating protrusion thereupon intermediate its extremities extensible through a corresponding jack opening and having a needle butt engaging an actuating portion on its lower extremity; a

5 10 15 20 25 30 35 40 45 50 55 60 65 70 75

pattern magazine fixedly mounted above each of said wheels and having outlet and inlet openings adjacent said wheel; and an individual pattern for each of said wheels adapted to be issued from the associated magazine to control the position of said jacks and, thus, the actuation of individual ones of said needles, said pattern having pattern determining openings intermediate its edges adapted to register with corresponding jack openings in an associated wheel to permit certain jack-actuating protrusions to pass therethrough in order that the needle butt engaging portions of said jacks may actuate associated needles of said machine.

5. In a pattern controlling system adapted to be utilized in conjunction with a rotary knitting machine having a fixed bed and a plurality of knitting needles mounted for rotation in a bank on said bed, the combination of: a plurality of rotatable pattern wheels mounted on said bed of said knitting machine adjacent said bank of needles, each of said wheels having a plurality of jack openings in its perimetrical wall intermediate the edges thereof and a plurality of jack receiving slots below said openings, said slots having portions engageable with said needles to permit said needles to rotate said wheel; a plurality of jacks mounted in each of said wheels, each of said jacks having a jack-locating protrusion intermediate its extremities and located in one of said jack openings in said perimetrical wall and a needle engaging portion in an associated slot in said pattern wheel for engagement with one of said needles; an individual pattern magazine mounted above each of said wheels having its outlet and inlet openings in close proximity to the perimeter of said wheels; and an individual pattern for each of said wheels, each of said patterns being constituted by an endless tape adapted to be fed from said magazine during rotation of the associated wheel, said endless tape having pattern determining openings formed therein intermediate its edges and registerable with said jack openings to permit outward movement of said jack-locating protrusions through said pattern determining openings of said tape.

6. In a pattern control system adapted to be utilized in conjunction with a rotary knitting machine having a bed and a rotatable bank of individually actuatable needles on said bed, the combination of: a plurality of pattern forming devices mounted on said bed at the perimeter thereof, each of said devices incorporating a plurality of needle actuating means adapted to determine the position of individual ones of said needles; and individual control means mounted on each of said devices and adapted to determine the position of said needle actuating means, each control means including a magazine and an endless tape, said magazine being mounted adjacent and over an associated pattern forming device and said tape having a loop engageable with an associated device.

7. In a pattern wheel adapted to be utilized in conjunction with a rotary knitting machine to control the actuation of the needles thereof, the combination of: a housing adapted to be rotatably mounted on said knitting machine, said housing having a perimetrical wall incorporating a plurality of jack openings intermediate its edges and incorporating a plurality of slots below said jack openings; a plurality of jack in said housing adapted to control the operation of associated needles of said knitting machine, each of said jacks having a jack-locating protrusion thereupon positioned for movement in an associated jack opening, and having a needle engaging portion thereupon located in an associated slot; and a continuous individual pattern magazine mounted adjacent and above said housing and engageable with said jacks to determine the position thereof with respect to said housing, said pattern being constituted by a continuous tape mounted in said magazine and having a loop partially encompassing said perimetrical wall and incorporating pattern determining openings registerable with said jack openings to permit the passage of said jack protrusions there-

through and the movement of said needle engaging portions of said jacks into operation positions in said slots to engage said needle.

8. In a pattern wheel adapted to be utilized in conjunction with a circular knitting machine, the combination of: a rotatable housing adapted to be mounted upon said knitting machine, said housing having a plurality of jack openings in a wall thereof and a plurality of jack receiving slots juxtaposed to said openings, said slots having needle engaging portions adapted to permit said housing to be rotated by the needles of said knitting machine; a plurality of needle actuating jacks mounted for movement in said housing in proximity to said jack openings and having jack-locating portions protruding through said jack openings; a magazine mounted above said housing and in immediate proximity thereto; and an endless tape having its major portion enclosed within said magazine at all times and having a loop engageable with the wall of said housing, said tape incorporating pattern determining openings intermediate its edges registrable with corresponding jack openings to permit the protrusion of said jack-locating portions through said openings in said tape.

9. In a pattern wheel adapted to be utilized in conjunction with a circular knitting machine, the combination of: a rotatable housing adapted to be mounted upon said knitting machine, said housing having a plurality of jack openings in a wall thereof and a plurality of jack re-

ceiving slots juxtaposed to said openings, said slots having needle engaging portions adapted to permit said housing to be rotated by the needles of said knitting machine; a plurality of pivotally mounted needle actuating jacks mounted for movement in said housing in proximity to said openings and having jack-locating portions protruding through said openings; a magazine mounted above said housing and in immediate proximity thereto; and an endless tape having its major portion enclosed within said magazine at all times and having a loop engageable with the wall of said housing, said tape incorporating pattern determining openings intermediate its edges registrable with the corresponding jack openings to permit the protrusion of said jack-locating portions of said jacks through said openings in said tape.
